UNITED STATES PATENT OFFICE.

WILLIAM HORN, JR., OF KEOKUK, IOWA.

WATER CUT-OFF FOR CISTERNS.

SPECIFICATION forming part of Letters Patent No. 339,651, dated April 13, 1886.

Application filed January 25, 1886. Serial No. 189,641. (No model.)

To all whom it may concern:

Be it known that I, WILLIAM HORN, Jr., of Keokuk, in the county of Lee and State of Iowa, a citizen of the United States, have invented a new and useful Improved System of or Process and Means for Water-Spout Cut-Offs for Cisterns, which is made, practiced, and used substantially as set forth hereinafter, and as shown in the accompanying drawings, in which--

Figure 1 is a vertical section of the improved parts. Fig. 2 is an external view of same. Fig. 3 is a sectional detail.

The object of this invention is to form an improved cut-off for water-spouts to cisterns, which can be set to throw water into or away from the cistern, and can be changed from time to time or during the continuance of a rain, and which will strain the water going to cisterns from leaves and other bodies.

To this end the invention comprises a main pipe, A, from the roof, with two branches, B C, connecting to the wasteway and the cistern, a cut-off part, D, pivoted at I, so that it may be turned to throw the water into or from the cistern, as preferred, a handle-lever, H, to turn part D, a spring-catch on handle H, and sockets or catches G G' for the same to engage with, and a strainer, F, hinged to one edge of part D, so that when that is turned one way, as in Fig. 1, the strainer will open from part D and close the water-way to the cistern, so as to strain the water, and when part D is turned the other way it will fall down against part D and leave the wasteway-passage open to the escape of all leaves and accumulations, which are made and arranged to operate together as shown.

The parts are substantially made of sheet metal, wires, and other suitable materials, as usual in the art.

The parts of the pipes A B C shown form a separate portion of the spouting, which can be connected with the several plain pipes as required, and form a separate article of manufacture and trade complete in itself, and ready for connection with the several pipes. The handle H is mounted on the end of a lever formed of heavy wire, which is bent to form a pivot for part D at each side of the pipe, and to form a hanging yoke inside below such pivots, descending to the bottom of part D. The handle H is fixed loosely on its lever and held suitably with a spring, i, so that the action of the spring will hold it in the socket G or G' so it cannot accidentally escape, but so that it can be drawn out, so as to release the lever to let it be turned the other way.

The several parts admit of modifications.

I claim--

1. The combination of turn-spout D, having a turn-lever, with spout A B C, having two cavities, G G', and with spring-catch knob H, substantially as and for the purpose set forth.

2. The improved water-spout cut-off having the pivoted part D, provided with a hinged strainer, F, and with an operative handle, H, having a catch, and cavities G G', adapted thereto to hold it in alternative positions.

WM. HORN, JR.
